UNITED STATES PATENT OFFICE

2,276,943

VACUUM CLEANER FLOOR MOP

Dewey M. Dow, Toledo, Ohio, assignor to Air-Way Electric Appliance Corporation, Toledo, Ohio, a corporation of Delaware

Application May 26, 1939, Serial No. 275,830

2 Claims. (Cl. 15—158)

This invention relates to vacuum cleaners and more particularly relates to a bare floor or wall type dust mop adapted to be used in connection with a wand type of cleaner or wand and hose attachment applied to an ordinary portable vacuum cleaner.

The object of this invention is to construct a more efficient type of bare floor or wall type dust mop.

Another object of this invention is to construct a dust mop in which all dust and dirt upon the surface will be urged toward and underneath the suction inlets of the brush and in which there is an individual suction inlet completely succeeded by a row or rows of brush bristles.

A still further object of the invention is to so arrange the suction inlets and brush bristle rows on the brush such that the dust and dirt particles by reason of the brush construction will not be prevented from entering the suction inlet or will not pass the bristle rows and suction inlets, but will in either direction of movement of the brush always positively urge the particles under the suction inlet.

Further objects of the invention will appear to those skilled in the art to which this invention appertains upon a reading of the specification which, taken in connection with the accompanying drawings, sets forth the preferred embodiment of the invention and preferred modifications thereof. It is to be distinctly understood that the disclosures set forth are not to be taken as a limitation of the invention, but all variations, modifications and alterations of structure coming within the spirit and scope of the invention are intended to be included herein and the invention is limited only by the appended claims.

In the drawings:

Fig. 1 shows a front elevational view of the floor mop assembly.

Fig. 2 is a side elevational view of the floor mop.

Fig. 3 is a vertical sectional view of the floor mop taken substantially along the line 3—3 of Figs. 2 and 4.

Fig. 4 is a bottom plan view of the brush portion of the floor mop assembly.

Fig. 5 is a vertical elevational view of one of the suction inlet tubes.

Fig. 6 is a top plan view of the suction inlet shown in Fig. 5.

Fig. 7 is a front elevational view of one of the modifications of the floor mop shown in Figs. 1—4.

Fig. 8 is a side elevational view of the modification of Fig. 7.

Fig. 9 is a vertical elevational view thereof taken substantially along the line 9—9 of Figs. 8 and 10.

Fig. 10 is a bottom plan view of the brush portion of the floor mop.

Fig. 11 is a front elevational view of a further modification of the disclosure of Figs. 1—4.

Fig. 12 is a side elevational view of the modification of Fig. 11.

Fig. 13 is a vertical sectional view thereof taken substantially along the line 13—13 of Figs. 12 and 14.

Fig. 14 is a bottom plan view of the brush portion of the floor mop.

Fig. 15 is an elevational view of the suction inlet embodied in the modification of Fig. 11.

Fig. 16 is a top plan view of the suction inlet of Fig. 11.

The subject matter of this invention constitutes an improvement over that shown and described in U. S. Patent 2,130,635 and in which the present inventor was one of the joint inventors and which is commonly owned by assignee hereof.

The floor mop 1, which constitutes the subject of the instant invention comprises essentially a two part separable construction whose length is considerably greater than its width. One of the two parts of the floor mop is a nozzle 2, having an exhaust outlet 3 which is connectible to an appropriate source of suction by either a wand or hose construction (not shown) singly, or in combination, all of which is well known to the art. The other of the two part construction is a brush and suction inlet device 4, which is removably secured to the nozzle portion 2.

The nozzle portion 2, has a mouth portion defined generally by lips or side wall portions 5 etc. which in the instant disclosure extend downwardly. Inserted in this aforesaid mouth portion and on the front and rear longitudinal walls defining the mouth portion, are a set or pair of fiber agitators 6, one only of which is shown, similar to those described in U. S. Patent 1,980,438. These agitators are retained in position on the walls of the nozzle by a spring clip secured to the walls of the nozzle by a plurality of holding means 7, which may be either rivets or screws.

The brush portion of the floor mop 1, comprises a back or supporting structure 8, whose external dimensions are exactly that of the nozzle mouth such that the wall portions; 9, 9, 9, 9 of the brush coincide exactly with the wall portion defining

the mouth of the nozzle. The brush back or support 8, has arranged therein a plurality of suction inlets 10, and a brush element 11. The suction inlets 10, comprise a hollow cylindrical rubber element 12, (Figs. 5 and 6) having a shoulder or flange portion 13, which is adapted to rest upon the bottom wall portion 14, of the brush back. The suction inlets are in reality inserts which can be removed and replaced when worn to obviate the purchase of an entirely new brush.

The brush portion per se of the floor mop is arranged in apertures 15. An individual brush tuft 16, is inserted in each aperture 15, and is held therein by a retaining element 17a, in the form of a wire that extends upward and overlays the top of wall portion 14, and is secured thereto. Each of the brush tufts 16 is set in a projection 17, that extends an appreciable distance below the bottom of the brush back 4. This projection serves to stiffen the individual brush tufts in order to increase the cleaning effectiveness thereof.

The brush back is provided with a plurality of suitable apertures 18, in which the suction inlets 10 are inserted and, as was previously indicated, the shoulder or flange portion 13 of the inlets rests upon the top of wall 14. It is essential that means be provided to prevent the tipping or buckling of the inserts and to this end a plate 20, which is suitably apertured as at 19, and in strict accordance with the spacing of apertures 18 in the brush back. Plate 20 fits snugly within the space provided by the wall portions 9, 9, 9, 9 of brush back 4, and has extensions or projections 21a that fit firmly within the upper end of the insert thereby firmly holding the insert in a fixed position. Plate 20 is appropriately embossed to receive flange portion 13 of the suction inlets.

Attention is at this point invited to the arrangement of the brush tufts and the suction inlets. It will be observed that the suction inlets 10 are spaced an appreciable distance apart. The brush tufts are arranged in a single substantially continuous row that passes between the several suction inlets. The row of bristles is such that only one side or only one-half of the inlet is surrounded by a bristles leaving the other half or side free. The inlets in effect are set in pocket formations A, A, A etc., as indicated and shown. The row of tufts or bristles is composed of a plurality of semi-circular wave-like formations and acts to prevent the possible escape of dust and dirt through brush passages to positively urge such dust and dirt under the suction inlets. In other types of bristle arrangements, the bristles themselves actually prevent the suction inlet, or inlets, drawing the dust and dirt upwardly into them by causing the dirt to get caught in the bristles, or by simply passing in between bristle rows without being definitely kept underneath the suction inlet and thereby compelling its being picked up. Irrespective of the direction of movement of the mop of the instant invention over the surface being cleaned, no dirt in the path of the brush can escape being picked up, and by reason of its construction, its action is universal and reduces by one-half the time necessary for cleaning. The suction inlets concentrate the suction over a restricted area thereby assisting in speeding the removal of dust and dirt. The brushes serve to utilize the full length of mop assembly which, in combination with the concentrated application of the suction, increases the cleaning effectiveness of the floor mop. Substantially one-half of the inlets are

effective during the forward movement of the brush and the remainder are effective during the reverse movement. The separability or detachability of the brush back from the nozzle is accomplished by the use of tensioned attaching elements 21. These elements are secured to the brush 4, by screws 22. Mounted on the end walls of the nozzle 2 are a pair of clips, or brackets 23, secured to the nozzle by screws 24, or other appropriate securing means. The spring element 21 has a shoulder portion 25 that fits over and above the upper part of clip or bracket 23. Clip, or bracket 23, is substantially U shaped and the spring element 21 fits within the U portion which, in cooperation with the shouldered portion thereof, retains the brush in engagement with the nozzle. When the brush back 4 is in engagement with the nozzle, the agitators 6, only one of which is shown, are in engagement with plate 20, which holds the inlets 10, etc. in position. Spring 21 tensions the entire assembly such that a firm, rigid, unitary organization is provided.

It is desirable that some means be provided on the floor mop assembly whereby the possibility of damage to it and objects of furniture, interior trim, etc., within the home is obviated. To this end a preferably semi-circular section of rubber 26 is provided. Bumper 26 is disposed about the periphery of the nozzle and is preferably of the non-marking type of rubber.

Figs. 7-10 disclose a modification of the structure just described. Fig. 7 shows the front elevational view of the floor mop generally indicated at 27. The floor mop, as in the previous instance, comprises a nozzle portion 28, provided with an exhaust 29, to which a conventional hose and wand, or hose alone, may be attached, which is connected to a convenient source of suction. The other part of the floor mop is the brush portion 30, carrying the brush bristles and suction inlets all as hereinafter set forth.

The nozzle 28, has a downwardly opening mouth as shown, which is defined by walls 31, 31 etc. Interiorly of the nozzle and secured to the forward and rearward longitudinally extended walls, a pair of fiber agitators 32 are arranged, one only of which is shown. These agitators are maintained in position on the aforesaid walls by a spring clip 33, which is secured thereto by means 35, which are preferably rivets but which may be screws, or any other appropriate means.

The nozzle, which is considerably longer than it is wide, is provided at its respective ends with a bracket 36, which is secured to the nozzle by rivets 37. The bracket 36 is U shaped, the function of which will be hereinafter set forth. Surrounding the nozzle is a mar-proof bumper 38, which is substantially semi-circular in cross section and whose function is to absorb the knocks and blows imposed on the nozzle and thereby prevent damage to itself and to objects of furniture and the interior trim within the home.

The brush portion of the mop 30 comprises a brush back 39, which has upwardly extending walls 40, 40 etc., which coincide directly with wall portions 31, 31 etc. of nozzle 28. The bottom wall 41 of the brush back is provided with a plurality of apertures 42 through which rubber suction inlets 43 are inserted, which are similar in shape to inlets 10, described in connection with Figs. 1-6.

Brush back 39 is further provided with a downwardly extending projection 44 in which brush tufts 45 are assembled in the manner described

in connection with tufts 16 above. The brush tufts are disposed in a continuous row across the bottom face of the brush back 30, in a zig-zag manner and in which the ends of the transverse, or obliquely extending portions 46 of the row are joined at the ends by a short longitudinally extending portion 47. Attention is invited to the fact that the apertures 42, in which suction inlets 43 are inserted, are placed in proximity of the apices of the zig-zags. The apertures and inlets are not in a continuous or single row as shown, although it is entirely possible to effect such arrangement. The converging obliquely extending rows form a pocket 48 in which the oblique rows of tufts have the tendency to urge dust particles entering the pocket 48 toward and underneath the opening of the suction inlet such that the particles will be carried away by the air stream entering the pocket.

Within the opening formed by the walls 40, 40 etc., of the brush back, a plate 49 is inserted which is apertured in such a manner as to conform to the inlet apertures 42. The plate 49 snugly fits within the aforesaid opening and holds the suction inlets 43 in position. To further facilitate the holding in position of the suction inlets and to prevent their tipping or buckling, the plate has projections 50 thereon which are apertured as at 51. The projections 50 extend into the inlet 43 an appreciable distance to accomplish the aforesaid result. The plate 49 is embossed to receive the flange position of the suction inlets, which aid further in keeping the suction inlets in position.

Mounted at the respective ends of the brush back are a pair of spring clips or retaining elements 52 secured to the back 30 by rivets or other securing means 53. The spring element 52 is shouldered as at 55, which shoulder engages the upper surface of U bracket 36. By this means plate 49 is firmly held in position by reason of the pressure applied thereagainst through the agitators 26 in the lip of nozzle pressing down on plate 49.

The full width of the brush is utilized in the above organization and by reason of the disposition of the row of tufts surface dust and dirt is positively urged underneath the suction inlet and no dust or dirt can possibly pass the row of tufts or bristles. As in Fig. 4, the suction inlets lie in the pockets 48 formed in the row of bristles, and dust must be urged underneath the opening and cannot possibly avoid doing so. It is not pushed away from the source of suction and since the latter is concentrated over a restricted area and the brush assists in urging the dust particles underneath the suction inlets, a maximum cleaning ability is provided. The brush functions in either direction of motion thereby lessening the labor involved by at least one-half in cleaning any given surface and also reducing the time the cleaning unit or source of suction must be in operation.

The modification disclosed in Figs. 11-16 shows a floor mop indicated generally at 56 and comprises a two part construction consisting of a nozzle portion 57 and a brush back portion 58. Nozzle portion 57 is provided with an exhaust extension 59 to which a hose or wand or a combination thereof may be attached, which is connected to a convenient source of suction.

The nozzle comprises a downwardly opening mouth defined generally by walls 60, 60 etc. The nozzle mouth length is considerably greater than its width and on each of the longitudinal walls 75

an agitator 61, only one of which is shown, is mounted, which may be similar in construction and form to that described and shown in U. S. Patent 1,980,438. The agitators are held in position in the nozzle by means of a spring clip 62 secured to the walls of the nozzle by rivets or other appropriate securing means 63. Extending about the nozzle exteriorly thereof is a rubber mar-proof bumper 64, intended to absorb the blows and shocks applied occasionally to the floor mop whereby injury is prevented to the mop and to articles of furniture and the interior trim within the home. A pair of U shaped bracket members 65 is applied to ends of the nozzle portion of the mop by screws 66, or other appropriate securing means. The function of the U shaped members will be hereinafter set forth.

Removably secured to the nozzle portion of the flor mop is a brush element 67 which has the same dimensions as the nozzle mouth. The brush element comprises a brush back 68 which has four upright walls 69, 69 etc., which correspond in shape to the nozzle walls 60, 60 etc. The brush back has a plurality of projections 70 integral therewith which extend obliquely across the brush back and in a zig zag fashion forming thereby triangular shaped openings 71. Fitted in appropriate apertures within the triangular shaped opening is a triangular shaped suction inlet 72. This suction inlet 72 is preferably of a mar proof rubber construction and comprises a body member 73 having a flanged top 74. The flange top 74 rests on the brush back portion 68 and is held in place by means herein-after described.

The brush proper of the brush portion comprises preferably a series of tufts 75 which are secured in apertures 76 in the manner described in connection with tufts 16 and as more particularly set forth in U. S. Patent 2,130,635. Other modes of assembling of the brushes may be employed if desired.

The brush portion of the mop is held in assembly relation with the nozzle by means of spring retaining elements 77 that are secured to the brush portion 67 by rivets 78, or other appropriate holding means. Each of the spring elements 77 has a shoulder portion 79 which rests upon the top of U element 65 and thereby retaining the nozzle and brush in assembled relation.

Fitted in the opening provided by the walls 69, 69 etc. and adapted to hold the suction inlets in position and to prevent their buckling, or collapsing, is a retainer plate 79 having a plurality of apertures 80, which are similar in shape to the apertures in inlets 72.

The plate 79 is provided with projection 81 which fits within the suction inlet to hold same in place. Plate 79 as well as plates 49 and 20 are embossed to receive the flange portion 74 and 13 of the suction 72 and 10 inlets which, in connection with the projections 81, 21 and 50, serve to maintain the suction inlets permanently in place and yet afford a single easy method of replacement.

When the brush portion 67 is assembled onto the nozzle 57, the agitator 61 bears down on plate 79, thereby preventing any relative motion of the several parts.

The brush tufts or bristles 75 and projection 70 in which they are mounted are shown with slight breaks at the apices of the zigzags, although in practical consideration the brush tufts form a continuous zigzag line across the face of the brush back. If so desired, the projection 70

may be made continuous as indicated by the dotted lines 82, and if the brush tufts employed do not completely fill the space indicated by the dotted lines, an additional tuft may be inserted in that space to thereby definitely provide an unbroken row of tufts.

The mop functions with equal facility during either a forward or a reverse stroke, thereby reducing by one-half the time necessary to clean a given surface. Dirt and dust is urged by the bristles underneath the suction inlets and cannot possibly slip between or past the brushes by reason of the continuous row of tufts.

That which is considered new, novel and useful, and which it is desired to protect by Letters Patent of the United States, is as follows:

1. A suction operated floor brush comprising an elongated brush back having a plurality of suction inlets arranged in a row extending longitudinally of the back, and bristle tufts projecting beyond the plane of the mouths of said inlets and mounted in said back in a substantially continuous row forming a series of alternately oppositely facing semi-circular brush pockets each embracing one of said inlets, whereby said inlets are divided into two series, one disposed on one side and the other on the other side of said row of bristles, and whereby said bristles will sweep toward one series of inlets when the tool is moved in one direction and toward the other series of

inlets when the tool is moved in the opposite direction, said suction inlets each having an opening the area of which is smaller than that of the pocket in which it is disposed.

2. A floor brush for use in connection with a nozzle having an elongated mouth, comprising an elongated brush back adapted to be removably secured to the nozzle over said mouth, a plurality of suction inlets in said brush back adapted to communicate with the nozzle and arranged in a row extending longitudinally of the back, and bristle tufts projecting beyond the plane of the mouths of said inlets and mounted in said back in a substantially continuous row forming a series of alternately oppositely facing brush pockets each embracing one of said inlets, whereby said inlets are divided into two series, one disposed on one side and the other on the other side of said row of bristles, and whereby said bristles will sweep toward one series of inlets when the tool is moved in one direction and toward the other series of inlets when the tool is moved in the opposite direction, said suction inlets each comprising a nozzle of yieldable material projecting beyond the face of the brush back to a plane near that of the tips of the bristles and each having a mouth area that is smaller than that of the pocket in which it is disposed.

DEWEY M. DOW.
